UNITED STATES PATENT OFFICE

JOHN H. LONSKY, OF YPSILANTI, MICHIGAN, ASSIGNOR TO CENTRAL SPECIALTY COMPANY, OF DETROIT, MICHIGAN, A CORPORATION OF MICHIGAN

SHOWER BATH TRAP

Application filed December 10, 1928. Serial No. 324,917.

The invention relates to certain classes of plumbing fixtures such as shower bath traps and the like where a drain pipe or other conduit is mounted in tile, concrete or other flooring and arranged flush therewith.

One of the objects of the invention is to provide a construction which will permit the drain pipe to be accurately positioned in the floor and permanently secured to the pipe line whether or not the latter is exactly perpendicular to the floor.

Another object is to construct a shower bath trap having a swivel joint connection to which the strainer tube is attached.

A further object is to provide a device in which the strainer tube may be removed from the pipe if desired after the floor is finished.

Another object is to provide improved means for draining into the trap any water leaking into the floor.

These and other objects are attained with the novel construction hereinafter more fully described and illustrated in the accompanying drawings, wherein

Figure 1 is a section through the trap showing the position of the same in the floor;

Figure 2 is a plan view of the leveling ring;

Figure 3 is a section on the line 3-3 of Figure 2.

Figure 4 is a fragmentary vertical sectional view through the trap showing the plug 41 applied thereto.

In accordance with my invention, the trap 10 has formed at its upper end the spherical seat 11 into which fits a separate leveling ring 12. The ring has a curved lower surface 13 corresponding to the seat 11 which enables the ring to be given a universal rocking movement with respect to the trap. The ring has interior threads 14 for receiving the threaded drain tube 15 which extends upwardly therefrom to the level of the floor.

The upper end of the trap 10 extends upwardly and outwardly beyond the spherical seat forming the top flange 16. Adjacent the spherical seat the flange has an inwardly extending annular shoulder 17 forming between the same and the ring a recess, the

bottom 18 of which is larger than the neck 19. Below the seat 11 the walls of the trap 10 are provided with internal threads 20. The main body portion of the trap may be made in any suitable manner to provide a return bend to the conduit in accordance with the usual practice. As shown the trap extends downwardly below the seat for a certain distance and has an outlet branch 23 extending upwardly to the outlet flange 24, establishing the water level in the trap at the line A—A.

The leveling ring 12 is provided with a series of drain slots 25 cut through the interior threads 14 at circumferentially spaced points. This permits any water which may collect above the leveling ring and outside of the drain tube 15 to drain through into the trap. The leveling ring 13 has an annular groove 27 above the threads 14 and a curved surface 28 below the threads. Supported within the annular groove 27 is a tubular member 29 which telescopically engages a second tubular element 30, the two forming a protecting seal on the outside of the threaded drain tube 15. The upper end of the drain tube flares outwardly at 30' and has at its top portion the annular groove 31 for receiving the outer edge of the strainer 32, which latter as shown has a depressed center portion 33. The strainer 32 is removably secured to the flange 30' by machine screws 34 or other means.

In installing the improved shower bath trap in a building the body portion of the trap 10 is mounted in the usual way beneath the floor level and the outlet flange 24 is connected to the sewer pipe 36 in the usual manner. In shower bath construction it is universal practice to use sheet lead beneath the floor and this is illustrated in the drawings by the reference numeral 37. The sheet lead is cut away to form an opening registering with the trap and the edges 38 of the aperture so formed are bent around the annular shoulder 17 which surrounds the leveling ring 12. The joint between the sheet lead and the trap body is then made water tight by pouring calking lead into the space between the annular shoulder 17 and the

leveling ring. Before this joint is sealed, however, the drain tube 15 is threaded into the leveling ring 12 and the latter is swiveled on the spherical seat 11 until the top of the drain tube and the strainer 32 is exactly level. By reason of this universal joint the drain tube may be leveled after the trap is installed in position and any inaccuracy in alignment of the trap when connecting the same to the plumbing may be easily compensated for by adjusting the leveling ring.

After the leveling ring is secured in final position by the calking lead the concrete base 39 of the floor may be poured around the drain tube but this concrete will be held out of contact with the threaded portion of the drain tube by the tubes 29 and 30. It is usual to provide the surface of the floor with tile which is indicated at 40 and arranged to be exactly flush with the top of the drain tube.

With the construction as above described there are many advantages over the usual construction of shower bath trap. The chief advantage resides in the fact that the adjustable leveling ring permits accurate leveling of the upper surface of the drain tube regardless of any misalignment in the body of the trap which is connected to the rest of the plumbing. Another advantage is that the drain tube may be removed if desired after the floor is laid, since the protecting tubular elements 29 and 30 keep the concrete from becoming embedded in the threaded portion of the drain tube. A further advantage resides in the provision of the drain slots 25 at the lowest point above the sheet lead, thus any water seeping through the tile or concrete will find its way through the slots 25 into the trap.

It is usual practice to test the plumbing in a building before the floors of the building are entirely completed and in order that the plumbing may be tested previous to the calking of the leveling ring in final position, it is necessary to provide an arrangement for sealing the upper end of the trap. With my construction this can be done by removing the leveling ring 12 and inserting a plug 41 threaded to engage the threads 20 in the upper portion of the trap. After the testing is completed the plug 41 is removed and the threads 20 have no further utility.

While I have described and illustrated a preferred embodiment of the invention, it is to be understood that the invention is not restricted to the specific details as above set forth, but is capable of embodiment in other structures which come within the purview of the claims appended hereto.

What I claim as my invention is:

1. A shower bath trap comprising a conduit having a spherical seat therein, a ring having a spherical surface engaging said seat, a flange on said conduit extending inwardly toward said ring forming an annular recess

therebetween with an enlarged bottom portion and a smaller neck portion and a cast metal joint between said ring and said flange.

2. A shower bath trap comprising a body portion having a spherical seat, a ring having a cooperating spherical surface engageable with said seat, said ring having internal threads slotted at intervals around the periphery thereof, a drain conduit threadedly engaging said ring and a tubular member surrounding said drain conduit and connected to said ring.

3. A shower bath trap comprising a body portion having an outwardly extending flange at the upper end thereof, a spherical seat on said body portion, a ring having a spherical surface engaging said seat, an annular flange on said conduit extending inwardly toward said ring and metal between said ring and said annular flange forming a joint therebetween.

4. The combination of a conduit permanently connected to the plumbing and adapted to be arranged beneath the floor, a second conduit adapted to extend through the floor, a ring removably secured to said second conduit and adjustably mounted on said first conduit and means for permanently locking said ring in predetermined relationship with said first conduit.

5. The combination of a conduit adapted to be arranged beneath the floor, a second conduit adapted to extend through the floor and having an upper portion adapted to be flush therewith, a ring threadedly connected to said second conduit, said ring having a universal connection with said first conduit and means for maintaining said ring in predetermined relation with said first conduit whereby the second conduit may be leveled with respect to the floor.

6. A shower bath trap including a strainer having a depending drain tube adapted to extend through a flooring and provided with external threads, a ring having internal threads engaging the external threads aforesaid, and means extending between the strainer and ring for preventing portions of the flooring from engaging the external threads on the tube.

In testimony whereof I affix my signature.
JOHN H. LONSKEY.
